UNITED STATES PATENT OFFICE.

WILLIAM H. WILDER, OF NORTHAMPTON, MASSACHUSETTS.

DESIGN FOR A SHADE FOR LAMPS OR LAMP-STOVES.

SPECIFICATION forming part of Design No. 23,808, dated November 13, 1894.

Application filed September 12, 1894. Serial No. 522,850. Term of patent 14 years.

To all whom it may concern:

Be it known that I, WILLIAM H. WILDER, a citizen of the United States, residing at Northampton, in the county of Hampshire and State of Massachusetts, have invented and produced a new and original Design for Shades or Covers for Lamps or Lamp-Stoves, of which the following is a specification.

My design is shown in the accompanying figure by a perspective view.

The leading feature of the design consists in a domeshaped shade or cover provided with a series of perforations and surmounted by a conical cap.

15 In the drawing, the shade or cover is of a

shape approximating a dome being largest at its base and rounding upwardly to the cap or apex. An ornamental cap surmounts the dome top. The dome has an ornamented surface and is made with rows of perforations 20 adding to the ornamentation.

What I claim is—

The design for a shade or cover for lamps or lamp stoves herein shown and described.

In testimony whereof I affix my signature in 25 presence of two witnesses.

WILLIAM H. WILDER.

Witnesses:

CLIFFORD H. STOCKWELL,
NORRIS S. BRYANT.
